HEATER

Bartholomeo De Lorenzo, Elyria, Ohio, assignor
to Foster Wheeler Corporation, New York,
N. Y., a corporation of New York

Application April 17, 1943, Serial No. 483,535

12 Claims. (Cl. 122—356)

1

This invention relates to heaters, and more particularly pertains to tubular heaters for heating fluids such as hydrocarbon oils and the like, although it is applicable to the heating of fluids generally.

The invention provides a tubular fluid heater of simple and economical design and construction in which substantially uniform heating of all the tubes in the furnace of the heater is effected.

The invention will be understood from the following description when considered in connection with the accompanying drawings, forming a part thereof, and in which:

Fig. 1 is a transverse vertical sectional view on the line 1—1 of Fig. 2 of a heater embodying the invention.

Fig. 2 is a longitudinal vertical sectional view taken on line 2—2 of Fig. 1, and

Figs. 3, 4 and 5 are vertical, transverse, sectional views taken on lines 3—3, 4—4 and 5—5 respectively, of Fig. 2.

Like characters of reference refer to the same parts in the several views.

Referring to the drawings, the heater has a setting including vertical side walls 10 and 11, sloping side walls 12 and 13, end walls 14 and 15, a roof 16 and a bottom 17. Suitable framework designated generally 18, supports the walls and roof of the setting. The walls of the setting enclose a furnace 19 which is fired, as shown, by fuel burners 20 and 21 located in the end walls 14 and 15 respectively, in the lower central portion thereof.

The side walls and roof are lined with fluid conducting tubular members which are heated principally by radiation from the products of combustion produced by the burners 20 and 21. Vertical side walls 10 and 11 have horizontally extending tubular members 22 and 23 respectively, supported adjacent thereto by the tube supports 24. The sloping side walls 12 and 13 have similar tubular members 25 and 26 respectively, hung adjacent thereto by supports 27, and tubes 28 are supported below the roof by hangers 29. The tubes adjacent the side walls and roof are connected by suitable return bend portions which may be disposed within the heater or outside of the end walls thereof.

The heater has a convection tube bank 30 above the bottom 17 which is located approximately midway between the side wall 10 and 11 and which extends the full length of the furnace. As shown, the convection bank comprises three superposed rows of tubes with the tubes of each

- row arranged in staggered relationship with respect to the tubes of the adjacent row. A baffle 31 is supported above the tube bank 30 by tile 32 which rest upon the upper rows of the tubes 32 of the bank 30. Walls 33 and 34 extend from the bottom 17 to the baffle 31 adjacent the tube bank 30 and enclose the sides of the convection bank to thereby form a passage 37 for the furnace gases. The ends of the baffle 31 and the walls 33 and 34 are disposed in spaced relationship to the end walls 14 and 15, to provide furnace gas openings or passages 35 and 36 through which the gases flow from the furnace into the convection heating passage 37 in which the convection tube bank 30 is disposed. From the passage 37, the gases flow into a central, downwardly extending gas flue 39, which discharges into a flue 40 which connects with a stack, not shown.
- 20 In the form of the invention illustrated, the tubes 30 of the convection bank have extended surface elements 41 on the portions thereof which extend between the ends of the baffle 31 and the gas flue 39. The extended surface elements 41 comprise longitudinally extending U-shaped or channel members welded to the aforesaid portions of the tubes, although other types or shapes of extended surface elements may be employed, if desired. The portions of the tubes 30 which are beneath the baffle 31 and adjacent the openings 35 and 36 are provided with a suitable or desired number of extended surface elements, while the other portions of the tubes 30 beneath the baffle 31 and which extend to the gas outlet 39, have a greater number of extended surface elements, approximately twice as many, as shown in Figs. 2, 3 and 4. With this arrangement, the heat absorbed by the convection tubes 30 is substantially equalized throughout their lengths.
- 30 The tubes 30 are supported at their ends by tube sheets 42 and 43, Fig. 2, and they are supported intermediate their ends by novel means. In the form shown, such novel supporting means comprises a plurality of relatively narrow metallic straps 44 which extend transversely about the extended surface elements 41 of the tubes of the upper and lower rows of tubes 30 and engage a substantial portion of the extended surface elements of the tubes of the intermediate row, as shown in Fig. 5. The straps 44 are made into loops of the desired lengths by welding their ends together, and the intermediate portions of the loops are brought into contact and are welded together as indicated at 45. The

loops are placed in lateral alignment and are welded together at their upper and lower portions as indicated at 46 and 47. The lower end of each strop is attached to a bar 48 by welds 49. These tube supports are fabricated and are placed in position, and the tubes 30 are passed through them and through the tube holes in the tube sheets. The tubes of the upper and lower rows extend through the loops while the tubes of the middle row extend between adjacent loops. The bars 48 rest upon the bottom 17 of the furnace. With this arrangement, the tubes are supported adequately intermediate their ends without being secured to the supporting straps, and one or more tubes may be removed and replaced at will without materially affecting the support of the adjacent tubes, as will be apparent from an inspection of Fig. 5.

In the form shown, the fluid to be heated flows through the heater in two separate streams. Fluid enters the convection bank 30 through an inlet 58, Fig. 1, and after flowing through part of the tubes of bank 30, the fluid flows through cross-over connection 51 to the wall tubes 22, and through these tubes in series, and through sloping wall tubes 25 and roof tubes 28 to outlet 52. Fluid flows similarly through the other side of the heater, entering at inlet 50, flowing through the other tubes of convection bank 30, through cross-over connection 53, through wall tubes 23, sloping wall tubes 26, roof tubes 28 and through outlet 52. Other fluid flow arrangements may be employed, if desired, and separate inlets and outlet connections may be utilized for each path of flow.

In operation, the hot products of combustion produced by the burners 20 and 21 stream from the burners and rise toward the roof. The gases are cooled by radiation of heat to the fluid conducting tubes in the furnace, and fall of their own weight and under the influence of the draft provided at the bottom of each end of the furnace, toward the gas openings 35 and 36. The gases thus form a symmetrical pattern with relation to the radiant heat absorbing tubes in the furnace and thereby effect substantially uniform heating of all the tubes in the furnace. By controlling the burners, the quantity of heating gases produced on either side of the furnace may be controlled and varied, to control the amount of heat supplied to the tubes on either side of the furnace and to vary the temperature to which the fluid flowing through either flow path is heated. The gases flowing from the furnace flow longitudinally over the tubes of the convection bank 30 from both ends of the furnace to the flue 39 and through the flue 40 to the stack. Due to the extended surface elements and their location and number, the tubes 30 are heated approximately evenly throughout their lengths.

Fluid heaters embodying the invention possess numerous advantages, among which the following may be mentioned. Inasmuch as little wall surface is exposed to direct radiant heat, the setting dimensions, particularly the height of the heater, are minimized with consequent economy in first cost. The sloping side walls eliminate corners which generally are cold spots in the furnace, and tend to provide a more even heat absorption throughout the radiant section of the heater. The sloping walls also make it possible to utilize a roof cover which is simple and inexpensive. No roof trusses are necessary and very little steel is required for the roof cover, although the top and sloping sides of the heater

are fully protected from the weather. The sloping walls and the roof arch may be made of light weight refractory material which reduces the weight of the setting so that the steel framework may be of light weight and of low cost. The side walls of the heater are supported directly on the foundation, and because these walls are comparatively low, they can be tied back readily to the framework and are practically self-supporting. Inasmuch as the heater lends itself to the use of a substantial amount of light weight refractory, the overall weight of the heater on its foundation is low.

No bridge walls are required inasmuch as the floor construction takes the place of a bridge wall. The floor construction is inexpensive because the tile composing the baffle is supported directly on the tubes of the convection bank. Although the tile composing the baffle shields the upper row of convection bank tubes to some extent, the heat passing through this baffle by conduction, compensates considerably for the shielding of the top row of tubes of the convection bank. Due to the use of the extended surface elements on the tubes of the convection bank, the number of tubes in the bank can be reduced with consequent reduction in the number of return bends or headers and joints. The convection bank tube sheet area is reduced because the outlet gas passage 37 is directly adjacent the first rows of convection tubes. In conventional heaters, the convection tube bank usually is elevated a considerable distance above the floor, thus requiring substantially more tube sheet area than is necessary with heaters embodying the invention. Due to the light weight and simple construction of the framework of the heater, the time required for erection is shortened. The arrangement of the radiant heating surface in the furnace approximates a half circle about the burners, so that all of the radiant tubes are approximately equi-distant from the burners. The cross-over connections which usually constitute an expensive item, are short and are of simple construction due to the fact that the bottom radiant tubes are close to the top of the convection tubes to which they are connected. The dimensions and arrangement of the setting are such that the expansion of the brick work is small and can readily be taken care of, so that expansion throughout the heater is not a difficult problem.

Although the invention is disclosed as embodied in a heater fired from both ends, it will be understood that heaters embodying the invention may be fired from one end only, if desired. Moreover, the convection tube bank may be disposed adjacent one or both of the side walls instead of approximately midway between these walls, as illustrated.

Changes may be made in the form, location and relative arrangement of the several parts of the heater disclosed without departing from the principles of the invention. Accordingly, the invention is not to be limited excepting by the scope of the appended claims.

What is claimed is:

1. Apparatus for heating fluids comprising walls forming a furnace, fuel burner means disposed in opposite walls for firing the furnace, fluid conducting tubular members adjacent other oppositely disposed walls adjoining said opposite walls, a bank of tubular members at the bottom of the furnace extending toward said opposite walls, a wall at each side of said banks of

tubular members, a baffle above said bank and said walls, said baffle and walls forming a passage for gas, said passage having terminal portions spaced from opposite walls to provide gas openings into said passage, the said bank of tubular members projecting from each end of said gas passage, longitudinally extending fins on those portions only of the tubular members of said bank which lie below said baffle, and means forming a flue to receive the gases flowing from said bank.

2. Apparatus for heating fluids comprising walls forming a furnace, fuel burner means disposed in opposite walls for firing the furnace, fluid conducting tubular members adjacent other oppositely disposed walls adjoining said opposite walls, a bank of tubular members at the bottom of the furnace extending toward said opposite walls, a wall at each side of said bank of tubular members, a baffle above said bank and said walls, said baffle and walls forming a passage for gas, said passage having terminal portions spaced from opposite walls to provide gas openings into said passage, the said bank of tubular members projecting from each end of said gas passage, longitudinally extending fins on those portions only of the tubular members of said bank which lie below said baffle, and means forming a flue to receive the gases flowing from said bank, there being a greater number of fins on those portions of the tubular members of said bank which are adjacent said flue than on those portions which are adjacent said gas openings to substantially equalize the heat input to the tubular members of said bank.

3. Apparatus for heating fluids comprising walls forming a furnace, each side wall having a vertically extending portion and a vertically and inwardly inclined portion above the vertically extending portion and connecting with the roof of the furnace, fluid conducting tubular members adjacent the side walls of the furnace, fuel burner means in the end walls of the furnace for firing the furnace, a bank of tubular members at the bottom of the furnace, a wall at each side of said bank of tubular members, a baffle above said bank and said walls, said baffle and walls forming a passage for gas, said passage having terminal portions spaced from the end walls to provide gas openings into said passage, the said bank of tubular members projecting from each end of said gas passage, longitudinally extending fins on those portions only of the tubular members of said bank which lie below said baffle, and means forming a flue to receive the gases flowing from said bank, there being a greater number of fins on those portions of the tubular members of said bank which are adjacent said flue than on those portions which are adjacent said gas openings to substantially equalize the heat input to the tubular members of said bank.

4. Apparatus for heating fluids comprising walls forming a furnace, fuel burner means positioned in at least one wall of oppositely disposed walls for firing the furnace, fluid conducting tubular members adjacent other oppositely disposed walls adjoining said first-mentioned oppositely disposed walls, gas passage forming means forming a gas passage at the bottom of the furnace extending toward said first-mentioned oppositely disposed walls, a bank of tubular members in said passage and extending toward said first-mentioned oppositely disposed walls, said passage forming means including a baffle above said bank of tubular members having terminal

portions spaced from said first mentioned oppositely disposed walls to provide gas openings from the furnace, and means forming a flue to receive the gases flowing from said bank.

5. Apparatus for heating fluids comprising walls forming a furnace, fuel burner means disposed in opposite walls for firing the furnace, fluid conducting tubular members adjacent other oppositely disposed walls adjoining said opposite walls, gas passage forming means forming a gas passage at the bottom of the furnace extending toward said opposite walls, a bank of tubular members in said passage and extending toward said first-mentioned oppositely disposed walls, said passage forming means including a baffle above said bank of tubular members having terminal portions spaced from said opposite walls to provide gas openings from the furnace, and means forming a flue to receive the gases flowing from said bank.

6. Apparatus for heating fluids comprising walls forming a furnace, fuel burner means positioned in at least one wall of oppositely disposed walls for firing the furnace, fluid conducting tubular members adjacent other oppositely disposed walls adjoining said first-mentioned oppositely disposed walls, gas passage forming means forming a gas passage at the bottom of the furnace extending toward said first-mentioned oppositely disposed walls, a bank of tubular members in said passage and extending toward said first-mentioned oppositely disposed walls, said passage forming means including a baffle above said bank of tubular members having terminal portions spaced from said first-mentioned oppositely disposed walls to provide gas openings from the furnace, longitudinally extending fins on the portion of the tubular members of said bank which lies below the baffle, and means forming a flue to receive the gases flowing from said bank.

7. Apparatus for heating fluids comprising walls forming a furnace, fuel burner means positioned in at least one wall of oppositely disposed walls for firing the furnace, fluid conducting tubular members adjacent other oppositely disposed walls adjoining said first-mentioned oppositely disposed walls, gas passage forming means forming a gas passage at the bottom of the furnace extending toward said first-mentioned oppositely disposed walls, a bank of tubular members in said passage and extending toward said first-mentioned oppositely disposed walls, said passage forming means including a baffle above said bank of tubular members having terminal portions spaced from said first-mentioned oppositely disposed walls to provide gas openings from the furnace, longitudinally extending fins on the portion of the tubular members of said bank which lies below the baffle, and means forming a flue in communication with said passage intermediate the opposite ends thereof to receive the gases flowing from said bank, there being a greater number of fins on those portions of the tubular members of said bank which are adjacent said flue than on those portions which are adjacent said gas openings to substantially equalize the heat input to the tubular members of said bank.

8. Apparatus for heating fluids comprising walls forming a furnace, fuel burner means positioned in at least one wall of oppositely disposed walls for firing the furnace, fluid conducting tubular members adjacent other oppositely disposed walls adjoining said first-mentioned oppositely

disposed walls, means forming a gas passage at the bottom of the furnace extending toward said first-mentioned oppositely disposed walls, a bank of tubular members in said passage and extending toward the first-mentioned oppositely disposed walls, said passage having a gas opening adjacent each of said first-mentioned oppositely disposed walls, and means forming a flue to receive gases flowing from said passage after passing in heat exchange relationship with the bank of tubes therein.

9. Apparatus for heating fluids comprising walls forming a furnace, fuel burner means positioned in at least one wall of oppositely disposed walls for firing the furnace, fluid conducting tubular members adjacent other oppositely disposed walls adjoining said first-mentioned oppositely disposed walls, means forming a gas passage at the bottom of the furnace intermediate said other oppositely disposed walls of the furnace, said gas passage extending toward said first mentioned oppositely disposed walls, a bank of tubular members in said passage and extending toward the first-mentioned oppositely disposed walls, said passage having a gas opening adjacent each of said first-mentioned oppositely disposed walls, and means forming a flue to receive gases flowing from said passage after passing in heat exchange relationship with the bank of tubes therein.

10. Apparatus for heating fluids comprising walls forming a furnace, each side wall having a vertically extending portion and a vertically and inwardly inclined portion above the vertically extending portion and connecting with the roof of the furnace, fluid conducting tubular members adjacent the side walls of the furnace, fuel burner means in at least one of the end walls of the furnace for firing the furnace, means forming a gas passage at the bottom of the furnace intermediate the side walls and extending toward said end walls, a bank of tubular members in said passage and extending toward the ends walls, said passage having a gas opening adjacent each of said end walls, and means forming a flue to receive gases flowing from said passage after passing in heat exchange relationship with the bank of tubes therein.

11. Apparatus for heating fluids comprising walls forming a furnace, fuel burner means positioned in at least one wall of oppositely disposed walls for firing the furnace, fluid conducting tubular members adjacent other oppositely disposed walls adjoining said first-mentioned oppositely disposed walls, means forming a gas passage at the bottom of the furnace intermediate two oppositely disposed walls and extending toward two other oppositely disposed walls, a bank

of tubular members in said passage and extending toward said two other oppositely disposed walls, said passage having a gas opening adjacent each of said two other oppositely disposed walls, and means forming a flue in communication with said passage and positioned in longitudinal space relationship to and substantial equi-distant from said openings to receive gases flowing from said passage after passing in heat exchange relationship with the bank of tubes therein.

12. Apparatus for heating fluids comprising walls forming a furnace, each side wall having a vertically extending portion and an inwardly inclined portion above the vertically extending portion and connecting with the roof of the furnace, fluid conducting tubular members adjacent the side walls and roof of the furnace, fuel burner means disposed in the opposite end walls of the furnace for firing said furnace, means forming a gas passage at the bottom of the furnace intermediate the side walls and extending toward said end walls, a bank of tubular members in said passage and extending toward the end walls, said passage forming means including a baffle above said bank of tubular members having terminal portions spaced from said end walls to provide gas openings from the furnace in communication with said passage, longitudinally extending fins on the portion of the tubular members of said bank which lies below the baffle, and means forming a flue in communication with said passage and positioned in longitudinally spaced relationship to and substantially equi-distant from said gas openings to receive gases flowing from said passage after passing in heat exchange relationship with the bank of tubes therein, there being a greater number of fins on those portions of the tubular members of said bank which are adjacent said flue than on those portions which are adjacent said openings to substantially equalize the heat input to the tubular members of said bank.
